REELING DEVICE

Harley C. Ralston, Cleveland, Thomas D. Williams, Garfield Heights, and Frank Mako, Cleveland, Ohio, assignors to The American Steel and Wire Company of New Jersey, a corporation of New Jersey

Application December 7, 1936, Serial No. 114,680

3 Claims. (Cl. 242—78)

This invention relates to reeling devices, and, more particularly, to reeling devices adapted for association with hot rod mills and the like. In the metallurgical industry, in the manufacture of attenuated metal stock, and, especially, rods and other elongated cylindrical objects, it is customary to introduce billets of metal, which have been heated to the proper temperature, to rolling mills for the purpose of elongating them and reducing the diameters thereof. In the case of rod mills, when a billet is reduced through a series of stands of rolls, the rod, as it emerges from the last pair of rolls, is of considerable length and travels at considerable speed, and it is necessary to provide some reeling means to coil the same.

To this end, driven reels are positioned some distance from the last pair of rolls in the rolling-train in line with the axis of the passes thereof to which the billet is introduced. Such reels are customarily synchronized in speed with the last pair of rolls so as to exert upon the hot stock no pulling tension, except as is hereinafter stated. Such reels usually comprise a revoluble base member upon which two sets of pins, or coil-forming members, are positioned in circular formations concentrically about the axis of rotation of such base member. A platform is provided on top of the base member through which the concentric sets of pins project. The incoming rod is laid between the two sets of pins and rests in coil formation upon the platform. The base member is rotated through a hollow shaft, and carried with it the pins, which, in turn, rotate the platform. After a coil has been wound, provision is made for discharging it from the reel. To this end, the platform is connected to a shaft, which projects through the hollow shaft by which the base member is rotated. This inner shaft is connected to any suitable actuating means whereby the platform may be moved upwardly away from the base member after the reeling operation is completed and the reel is at rest. The movement of the platform is such as to bodily lift the coil of rod to a plane substantially above the uppermost extremities of the coil-forming pins, whereby it may be transferred to any suitable conveyor mechanism.

In operation, these conventional types of reels present certain objectionable features, which result in a considerable loss in material, time, and labor. The principal of these objections lies in the fact that after the end of the rod leaves the last pair of rolls in the rolling-train, the stock remaining between the reel and the last pair of rolls must be wound by the rotation of the reel, which tends to exert a pulling tension thereupon in the absence of the forwarding assistance furnished by the rolling mill. These free ends of the hot rods, usually amounting to 75 feet or

more, are caused by the pull of the reel to become tightly wound about the upper extremities of the inner circle of pins thereof. Since the circle defined by the upper limits of the pins is usually of less diameter than that defined by their base portions to facilitate stripping the coil, the rod that is wound about the top portions thereof is coiled to a diameter smaller than the convolutions comprising the main body of the coil. When such a coil is stripped, these terminal portions of the rod, coiled to a smaller diameter, fall to the inside of the coil, and become tangled with the other convolutions thereof, which necessitates that they be removed as scrap.

It has also been proposed to make a reel on the revoluble base of which coil-forming pins are fixedly mounted to lean outwardly, so that any wire coiled about the upper extremities of such pins will form convolutions having a diameter equal to, or greater than, the mean diameter of the coil of which it is a part. The extremities of the fixed coil-forming pins, however, they may be disposed to form uniform convolutions of wire, collectively occupy an area commensurate with—in fact, greater than—that of such convolutions, and tend to bind the latter to the disarrangement and entanglement of the coil. It will be appreciated that the incoming rod cannot be controlled so as to engage the very extremities of the canted pins, and, hence, must first encounter them a suitable distance below such extremities. At this point, the pins collectively define a smaller area than that defined by their extremities. The coil is thus wound to a lesser diameter than that of the area defined by the pins' extremities collectively. It is obvious that, since the larger must pass through the smaller in discharging a bundle, disruption of the coil will result.

The reel of the present invention has been designed to overcome the objectionable features set forth above, and has for its primary object, the provision of a reel whereon perfectly uniform coils of rod may be formed, and wherein the terminal convolutions of said rod are constrained to conform in size and shape to the convolutions comprising the body of the coil.

It is another object hereof to provide a reel which will form uniform coils of rod throughout, and which will permit of readily discharging the coil without sacrificing any portions of the latter, and without disfiguring any portions thereof.

Other objects and advantages will be apparent from the following description, with reference to the accompanying drawing in which:

Figure 1 is a partial plan and partial plan-sectional view of a reel made in accordance with the present invention; the section having been taken along line I—I in Figure 2.

Figure 2 is a mid-sectional elevational view of the device illustrated in Figure 1.

Referring more specifically to the drawing in which like reference characters refer to like parts throughout, the numeral 1 designates a revoluble base member, which is secured upon a hollow shaft 2, for rotation thereby. Carried in suitable apertures adjacent the periphery of the base member 1 is a plurality of pins 3, mounted equidistantly in circular formation concentrically about the axis of rotation thereof. Disposed inwardly of this circle of pins, also in circular formation about the axis of rotation, is disposed a plurality of apertures 4 extending through the base member, and adjacent which are positioned pivot-bearings 5 integral with the latter.

- 10 A plurality of arms 6 are positioned within the apertures 4 between the pivot-bearings 5, and are secured for oscillation therein about hinge-pins 20 7. The portions 8 of the arms 6 falling within the apertures 4 are provided with oblique bearing faces 9, which engage complementary faces upon the innermost walls of the apertures in the base member 1, so as to cant the outer extremities of the arms outwardly toward the pins 3.

Disposed on top of the base member 3 is a platform 10 in which are provided apertures 11 and 12 for the accommodation of the pins 3 and the arms 6, respectively. Disposed co-axially within the hollow shaft 2, and extending through the base member 1, is a second shaft 13, which is secured to the platform 10 so as to raise the same for purposes to be described hereinafter. The innermost portions of the apertures 12 within the platform are sloped to conform to the canted disposition of the arms 6, and are provided with inserts 14 of bearing metal, which are normally adapted to engage the latter.

- 40 In operation, the lead end of a rod is introduced to the reel, which is then driven through the hollow drive shaft 2 at a high speed rate, corresponding to that at which the rod is being delivered by the last pair of rolls. The rod is directed to the rotating reel through a usual guide 45 15, which is disposed to "pour" the incoming rod within the annular space between the pins 3 and the arms 6, so as to form a coil 16 upon the platform 10. At the conclusion of the coiling operation, the rotation of the reel is stopped, and the shaft 13 is actuated through any suitable mechanism (not shown) to raise the platform supporting the coil 16 to a position, such as is shown in dotted lines, Figure 2. As the platform is lifted upwardly, the apertures 12 cause the arms 6 to retract inwardly away from their normal canted-position, toward each other. The coil is freed as the arms are caused to assume a position also shown in dotted lines, Figure 2. The coil may 60 then be removed from the elevated platform, which thereafter may again be lowered, and the operation repeated.

It will be seen from the above that the normal disposition of the arms 6, when the platform 10 is in lowered position adjacent the base member 1, is such as to coil the rods uniformly throughout their length, including the terminal portions thereof last to emerge from the rolling mill. By the outwardly-canted disposition of the arms 6, the terminal portions of the rod are wound in convolutions having a diameter substantially equal to the mean diameter of the coil, and by their own weight are caused to drop down into a satisfactory position upon the latter. All of the

stock, therefore, that has hitherto been rendered unusable, is preserved and handled so as to require that none of it be scrapped. Furthermore, the inward recession of the arms 6, during the discharging operation, provides that the coil be cleanly released, precluding disfigurement of the stock, and insuring against binding, tangling, and other complications, in stripping.

The apertures 4 in the base member 1, within which the arms 6 are adapted to oscillate, are 10 intentionally made of considerable size so that any dirt or other foreign matter, which may collect upon the base member 1 during the operation of the reel, can be cleaned-out to insure free movement of the arms 6 at all times. The bearing 15 plates 14 in the platform apertures 12 are made replaceable, whereby the proper positioning and supporting of the arms 6 may at all times be maintained, and wear compensated for. It is also desirable that the hinge-pins 7, and their bearings 20 in the members 5 and arms 6, be made of wear-resistant material; such as, of bronze bushing material. The latter also avoids any possible corrosive-action setting in after the reel is flushed with water. In this manner, a free pivotal action 25 is assured at all times, and lost-motion is obviated.

It is apparent that many changes may be made in the foregoing embodiment of the invention without departing from the true spirit thereof. 30 Therefore, it should be borne in mind that this description is merely illustrative in nature, and that the invention hereof is not to be limited except insofar as is necessitated by the prior art, and by the recitation of the following claims 35 when interpreted in view thereof.

We claim as our invention:

1. A coiling device comprising a revoluble base member, a platform positioned adjacent said base member, a plurality of arms pivotally secured to 40 said base member and extending through said platform, means to move said platform toward and away from said base member, and means rendered effective by said movement for oscillating said arms toward and away from each other. 45

2. A reeling device comprising a revoluble base members, a platform disposed above said base member, a plurality of pins rigidly affixed to one side of said base member and extending substantially perpendicular thereto and through said 50 platform, a plurality of arms pivotally secured to said base member and extending through said platform, means for moving said platform toward and away from said base member, and means rendered effective by said movement to oscillate 55 said arms toward and away from each other.

3. A reeling device comprising a revoluble base member, a plurality of pins extending perpendicularly from one side of said base member in spaced relation around the axis of rotation thereof, a plurality of arms pivotally carried upon the same side of said base member within the enclosure of pins in concentric spaced relation therewith, unitary material-receiving means positioned above said base member about said pins and arms, means for moving said material-receiving away from said base member substantially in an axial direction along said pins, and means associated with said last-named means rendered effective by the movement of the latter to move said arms toward each other. 65 70
